UNITED STATES PATENT OFFICE.

CLIFFORD H. TUTTLE, OF ENGLEWOOD, NEW JERSEY, ASSIGNOR TO TUTTLE & BAILEY M'F'G. CO., OF BROOKLYN, NEW YORK, A CORPORATION OF NEW YORK.

DESIGN FOR A PICTURE-FRAME.

52,231.

Specification for Design. Patented July 23, 1918.

Application filed April 12, 1918. Serial No. 228,272. Term of patent 7 years.

To all whom it may concern:

Be it known that I, CLIFFORD H. TUTTLE, a citizen of the United States of America, residing in Englewood, in the county of Bergen and State of New Jersey, have invented a new, original, and ornamental Design for a Picture-Frame, of which the following is a specification, reference being had to the accompanying drawing, forming part thereof.

The figure is a plan view of a picture frame, showing my new design.

I claim:

The ornamental design for a picture frame, as shown.

In witness whereof I have hereunto signed my name.

CLIFFORD H. TUTTLE.
